CAPPING MACHINE

John P. Anderson, Medina, N.Y., assignor to American Can Company, New York, N.Y., a corporation of New Jersey

Filed Feb. 15, 1967, Ser. No. 5,829

Term of patent 14 years

(Cl. D94—3)

FIG. 1

FIG. 2

FIG. 3

FIGURE 1 is a perspective view of a capping machine showing my new design;

FIGURE 2 is a left side elevational view thereof; and

FIGURE 3 is a front elevational view thereof.

The undisclosed side of the capping machine is the same in appearance as the side shown, and the top and rear surfaces thereof are substantially flat and plain.

I claim:

The ornamental design for a capping machine, substantially as shown and described.
